(57) **CLAIM**

The design for a tree and plant watering device, as shown and described.

DESCRIPTION

FIG. 1 is a perspective view of the ornamental tree and plant watering device of the present invention.

FIG. 2 is a side view of the ornamental tree and plant watering device of the present invention.

FIG. 3 is a front view of the ornamental tree and plant watering device of the present invention.

FIG. 4 is a back view of the ornamental tree and plant watering device of the present invention.

FIG. 5 is a top view of the ornamental tree and plant watering device of the present invention; and,

FIG. 6 is a bottom view of the ornamental tree and plant watering device of the present invention.
